CONTAINERS, SUCH AS BOXES, BASKETS
AND THE LIKE

Alice Gram Robinson, Washington, D. C.

Application January 30, 1957, Serial No. 637,215

5 Claims. (Cl. 224—46)

This invention relates broadly to containers, such as boxes, baskets and the like, which are intended and constructed to contain sewing materials and devices, tools, or other working implements. The invention is particularly described herein as a sewing box but this is done only to illustrate the invention and it is to be understood that the invention is of general application to, and utility with, containers, boxes, baskets and the like for all purposes.

It has been a principal object of this invention to provide a container, which is particularly described herein as a sewing box, which is easily portable, having a cover means which may be closed to protect the materials and devices contained in it, and which is so constructed that the cover means, when opened provides legs or supports on which the box or container rests in order to permit ready access to the box or container part of the device. Other objects and features of the invention will be made apparent in the following specification and by the annexed drawings, in which:

Fig. 1 is a perspective view of the sewing box provided by the invention, the cover means being shown in closed position;

Fig. 2 is a perspective view of the sewing box with the cover means in open position to provide a support for the sewing box;

Fig. 3 is a vertical sectional view of the sewing box with the cover means in open, supporting position;

Fig. 4 is a partial view of one of the covers in open position, showing also a modified form of the invention, and

Fig. 5 is an enlarged broken cross-sectional view taken substantially on the line 5—5 of Fig. 3 showing a form of hinge that may be used with the invention.

The sewing box provided by my invention comprises a box-like body part 2 having side walls 4, 6, end walls 8, 10 and bottom 12. The side walls 4, 6 extend slightly beyond the end walls at both ends, as indicated at 13, for a reason which will be explained fully hereinafter. This body part 2 is preferably a rectangular parallelepiped in shape with the side and end walls extending upwardly at right angles from the bottom. The side and end walls are preferably of relatively small height with respect to the area of the bottom, thus providing an essentially tray-like or shallow box. A partition 14 extends between the side walls 4, 6 midway between the ends and divides the box part into two compartments. At its central part this partition is provided with an opening 16 which is disposed below the upper surface of the partition and which is elongated in order to permit the hand of the user to be passed through it when the sewing box is to be lifted. Any desired arrangement of drawers, receptacles and the like may be built into or positioned within the two compartments defined by the partition 14 and may be used, as desired, for the reception of sewing articles and materials, tools or the like.

Additional handle means are provided by the invention for use in lifting the sewing box, and are positioned at

2

each end of the bottom part 12 exteriorly of the box part. One of these handles is positioned at each end of the box and these two handles are shown at 20, 22. These handles are preferably formed integrally with the bottom part 12 and extend outwardly from the respective ends thereof at the central parts of such ends and beyond the ends of the side walls 4, 6. The handles are elongated transversely of the box part to provide openings within which the user's hands may be inserted to lift the sewing box.

Means are provided by the invention for covering the normally open top of the sewing box and such means comprise two cover members 30, 32 which are respectively hinged, at their one ends, at the opposite ends of the box part 2 between the side wall extensions 13 on hinge or pivot means 31, clearly shown in Fig. 5, positioned closely adjacent the upper edges of the side walls. Each of the two cover members is of such length that it extends from its pivotal support to the nearest side of the central partition 14 where it rests on suitable stops 33. Each cover member is formed in its outer edge with a central recess 34. Those recesses register with each other when the cover members are in closed positions, as shown in Fig. 1, and when in such position they are adjacent the hand aperture 16 in partition 14, thus permitting a user of the sewing box to insert his hand through the aperture 34 to grasp the handle means provided by aperture 16.

Each of the cover members 30, 32 has formed therein an opening 36 which is elongated laterally of the cover member and has such dimensions and is so positioned that when the cover members are moved from their closed positions to their fully opened positions in which they abut the end wall members the handle members 20, 22 on the ends of the box part pass through these openings 36 and extend therethrough outwardly of the cover members, which are now in vertical position as shown in Figs. 2 and 3. It will be apparent that in this open position the cover members form legs or supports holding the box part in an elevated position in which it is readily accessible. Also, when the cover members are in this open, supporting position the handles 20, 22 which extend therethrough may be grasped by the user in order to move the sewing box from place to place.

In a modified form of the invention shown in Fig. 4, each of the handles 20, 22 is provided, within its central aperture, with a locking member 40 which is supported on a pivot 42 for movement from the plane of the handle 22 to a position outside that plane and in which it holds the cover member in opened position.

It is believed that the construction and mode of operation and use of my invention will be clearly understood from the foregoing specification and that no further description of the operation and use of the device is required.

While I have described and illustrated certain embodiments of the invention it will be apparent to those skilled in the art that other embodiments, as well as modifications of those disclosed, may be made and practised without departing in any way from the scope of the invention, for the limits of which reference must be made to the appended claims.

What is claimed is:

1. A combined box and stand comprising a box part having side walls, end walls and a bottom, two cover members, each of which is pivoted at its one end adjacent the upper edge of an end wall of the box part, said cover members being movable from closed positions in which they close the open top of the box part to open positions in which each is in substantially face-to-face abutment with the outer face of an end wall of the box part and in which the covers provide a support for the box part, a

handle member extending outwardly from each end of the box part, each of said cover members having an aperture therein through which one of said handle members extends when the cover members are in open positions.

2. A combined box and stand according to claim 1 in which the handle members are in the plane of the bottom of the box part and are adjacent the central part thereof.

3. A combined box and stand according to claim 1 in which each handle member has an aperture therein, and comprising in addition a member pivotally mounted in the aperture in each handle member and being movable from a position in the plane of the handle member to a position out of such plane in which it holds the associated cover member in opened position.

4. A combined box and stand comprising a box part having side walls, end walls and a bottom, said side walls extending beyond the end walls at both ends of the box part, a handle extending outwardly from the box part at each end thereof and being in the plane of the bottom and at the central part thereof, a partition extending transversely of the box part midway between the end walls thereof and having an aperture therein below the upper surface thereof and positioned centrally between the side walls, two cover members each of which is pivoted at its one end between the extending parts of said side walls at one end of the box part and adjacent the upper edges of said side walls, said cover members being movable to closed positions closing the open top of the box and to open positions in which they are in substantially face-to-face abutment with the outer faces of the end walls of the box part to provide supports for the box part, each of said cover members having a recess in the free end edge thereof positioned midway of said free end edge which

recesses permit access to the aperture in said partition when the cover members are in closed positions, each of said cover members also having an aperture therein which is so positioned that one of said handle members extends therethrough when the cover members are in open positions.

5. A combined box and stand comprising a box part having side walls, end walls and a bottom, a fixed partition extending transversely of the box part midway between the end walls thereof and being of substantially the same height as the side and end walls, an aperture in the central part of said partition below the upper edge thereof and below the upper edges of the side and end walls for the reception of the hand, two cover members pivoted at their one ends adjacent the opposite end walls of the box part and movable to closed positions in which their free ends are adjacent each other and adjacent said partition, each cover member having a recess in the free end edge thereof adjacent the central part thereof, which recesses are adjacent the aperture in said partition when the cover members are in closed positions to thereby permit access to said aperture, said cover members being of such length that when moved to open positions in which they are substantially in face-to-face abutment with the outer faces of the end walls of the box part they extend below the bottom to provide supports for the box part.
